F. EVANS & M. CAMPBELL.
PHONOGRAPHIC RECORD HOLDER.
APPLICATION FILED MAR. 6, 1913.

1,101,623.

Patented June 30, 1914.

UNITED STATES PATENT OFFICE.

FRED EVANS, OF SUMMIT, AND MALCOLM CAMPBELL, OF ENGLEWOOD, NEW JERSEY,
ASSIGNORS TO PATENTED DEVICES COMPANY, OF NEW YORK, N. Y., A CORPORATION
OF NEW JERSEY.

PHONOGRAPHIC-RECORD HOLDER.

1,101,623.

Specification of Letters Patent. Patented June 30, 1914.

Application filed March 6, 1913. Serial No. 752,398.

To all whom it may concern:

Be it known that we, FRED EVANS and MALCOLM CAMPBELL, residing at Summit and Englewood, in the counties of Union and Bergen and State of New Jersey, respectively, have invented certain new and useful Improvements in Phonographic-Record Holders, of which the following is a specification.

10 This invention relates to a cabinet or holder particularly adapted for containing a number of phonographic records of the disk type, and a particular object of the invention is to provide a cabinet within which the records may be efficiently protected against dust and other physical damage, and to arrange the parts of the cabinet in such manner that individual records may be readily and conveniently found.

20 With these objects in view, the invention comprises a plurality of separately movable receptacles, each adapted to contain preferably one disk, each receptacle having a title-bearing piece attached thereto, and each receptacle being normally fitted closely between two spaced walls or partitions so that the partitions will close the receptacles and exclude dust. The several receptacles are adapted to be swung easily from between the respective partitions into a position wherein the records may be readily removed, the receptacle by its swinging position incidentally indicating the proper receptacle into which the record is to be returned.

30 A further object of the invention is to provide a cabinet of the kind described which shall be cheap to manufacture, which shall be substantial, practical, and of an ornamental appearance, and in which is provided a simple locking device for retaining all of the receptacles in a locked condition between the walls or partitions when not in use.

35 Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which we have shown a merely preferred form of embodiment of the invention: Figure 1 is a side elevational view of the record cabinet constructed in accordance with the provisions of this invention and parts thereof being shown in vertical section 60 for disclosing details of the structure, one of the record receiving receptacles being shown swung open in dotted lines; Fig. 2 is a horizontal sectional view taken on the plane of line II--II of Fig. 1, and illustrating in dotted lines one of the receptacles swung open; Fig. 3 is an enlarged transverse sectional view taken on the plane of line III--III of Fig. 1 for illustrating the operation of the locking device; and Fig. 4 70 is a similarly enlarged, vertical, fragmentary, sectional view of the parts shown in Fig. 3.

Referring to the drawings for a detailed description of the structure illustrated, the reference numeral 1 indicates a pedestal of any suitable or ornamental design upon which rests base plate 2 of the cabinet. The base plate 2 is preferably disk shaped, to diametrically oppositely disposed marginal 80 portions of which is secured the opposite lower ends of a U-shaped frame 4. This frame may comprise preferably a metallic rod of substantial proportions bent into U-shape and having its opposite ends threaded 85 and introduced into apertures formed in the base plate 2 and held rigid therewith by suitable locking means 5, so that the legs of the U-shaped frame extend vertically upwardly from the base plate in substantially 90 parallel planes. A plurality of partitions or platforms 6 are mounted upon the legs of the frame 4. These platforms preferably each comprise a sheet metal member cut to the same diameter as the base plate 2, and 95 being apertured to receive the legs of the frame so that the various platforms are arranged in axial alignment one above the other. Spacing sleeves 8 are fitted upon the legs of the frame for spacing the platforms 100 uniformly apart.

Between each of the platforms 7 is disposed a separately formed ring-shaped receptacle 9 having a hinge member 10 at one

margin thereof, and a retaining member 11 at a diametrically opposite point in the margin thereof. The hinge members 10 are adapted to encircle the spacing sleeves 8 on one of the legs of the frame so as to constitute a substantial pivot about which the receptacle may swing bodily from its normal position within the cabinet as illustrated in full lines in Fig. 2, to the position illustrated in dotted lines in said figure. The retaining members 11 are formed with notches 12 adapted to engage about the opposite leg of the frame 4 for limiting the movement of the receptacles in one direction and thereby determining the normal position of the receptacles. These retaining members 11 also preferably are extended and bent diagonally downward as at 13, to provide surfaces which may be readily inspected and which may conveniently contain some designation, either name or number, of the particular record contained within the receptacle to which it is attached. The members 11 may also conveniently 25 serve as handles by which the receptacles may be swung.

A locking device is arranged for operating upon all of the receptacles simultaneously for retaining them in normal position. Any suitable device may be employed for this purpose, but we preferably utilize the structure illustrated in the drawings which comprises a metallic rod or wire having a straight intermediate portion 3 extending vertically of the structure, having its opposite ends bent laterally and formed into hinge portions 14 and 15 engaging about the leg of the frame 4 adjacent the retaining members 11. The hinge portion 14 at the lower end of the locking device preferably engages the leg of the frame beneath the base plate 2. The hinge portion 15 at the upper end of the locking device preferably engages the leg of the frame 4 above the uppermost partition or platform of the structure and is formed with a laterally extending portion 16 having a lug 17 formed thereon adapted to engage over one edge of the uppermost platform for retaining the locking device in a locked position, as will be described in connection with Fig. 3. The portion 16 is preferably made as an extension of the remaining portion of the locking device which is formed so that the hinge portion 15 will comprise a torsion spring.

In the drawings the locking device is shown in full lines in an unlocked position. In Fig. 3 the locking device is shown in dotted lines in locked position. Referring to Fig. 3 it will be seen by swinging the portion 16 of the locking device in the direction of the arrow, the outer end thereof comprising the vertical section 3 of the rod will engage with the edges of the partitions 6 before the lug 17 reaches the edge of the

platform. The locking device must therefore be sprung through the medium of the torsion spring afforded in the pivot portion 15 until the lug 17 is snapped over the edge of the platform as illustrated in dotted lines. The engagement of the vertical portion 3 of the locking member with the edges of the platforms will dispose the portion 3 close behind a portion 7 formed on the member 11, so as to prevent the accidental movement of the receptacles out of normal position so long as the lug 17 remains snapped over the edge of the uppermost platform. A pair of sleeves 19 are preferably fitted about the legs of the frame above the uppermost platform to serve as compression members, if desired, between which, and the upper surface of the base plate 2, the platforms may be clamped by the locking means 5.

Each of the receptacles 9 is preferably formed of a ring shaped wall 20 upstanding from the outer periphery of a floor portion 21, the height of the wall portion 20 being just sufficient for the passage of the receptacle between the opposing surfaces of the platforms 6. The fit is supposed to be snug so as to exclude a circulation of air and dust, to the end that the record may be efficiently preserved.

The floor portions 21 of the receptacle are cut away for the greater portion of their area concentric with the center thereof so as to facilitate removal of the disks when the receptacles are swung outwardly, as will be appreciated. This removal of material decreases the expense of manufacture and materially reduces the weight of the structure.

As many changes could be made in the above construction and many apparently widely different embodiments of this invention could be made without departing from the scope thereof, it is intended that all matter contained in the above description or shown in the accompanying drawing shall be interpreted as illustrative only and that the language used in the following claims is intended to cover all of the generic and specific features of the invention.

Having thus described our invention what we claim as new and desire to secure by Letters Patent is:

1. A record cabinet comprising a base, a pair of standards projecting upwardly from said base in spaced relation, a plurality of separately formed receptacles, a plurality of disk-shaped horizontally disposed partitions supported between said standards in substantially parallel relation separating said receptacles, one of said standards comprising a common pivot for all of the receptacles, the other standard constituting a stop for limiting pivotal movement of the receptacles in one direction, and means carried by the

second standard adapted to be moved into position for retaining the receptacles against movement in the other direction.

2. A record cabinet comprising a base, a pair of standards projecting upwardly from said base in spaced relation, a plurality of separately formed receptacles, one of said standards comprising a common pivot for all of the receptacles, the other standard constituting a stop for limiting pivotal movement of the receptacles in one direction, and means rotatable about the second standard comprising a lock for retaining the receptacles against movement in the other direction.

3. A record cabinet comprising a pivotally mounted receptacle having a member projecting laterally therefrom, a stop member adapted to be engaged by said laterally projecting member for limiting the pivotal movement of said receptacle in one direction, and means carried by said stop member adapted to be adjusted into position engaging said laterally projecting member for retaining the receptacle against movement in the other direction.

4. A record cabinet comprising a plurality of separately formed pivotally mounted receptacles, a member in the path of all of said receptacles serving as a common stop member for said receptacles to limit movement of the receptacles in one direction, and a latch pivotally mounted upon said stop adapted to be moved into position for retaining the receptacles against movement in the other direction, said latch comprising a section of wire extending past said receptacles disposed substantially parallel to the length of said stop and having its opposite ends bent into pivotal engagement with said stop.

5. A record cabinet comprising a plurality of separately formed pivotally mounted receptacles, a member in the path of all of said receptacles serving as a common stop member for said receptacles to limit movement of the receptacles in one direction, and a latch pivotally mounted upon said stop adapted to be moved into position for retaining the receptacles against movement in the other direction, said latch comprising a section of wire extending past said receptacles disposed substantially parallel to the length of said stop and having its opposite ends bent into pivotal engagement with said stop, and having at least one of said ends extended for providing a resilient means to maintain said latch in one of its positions.

6. A record cabinet comprising a plurality of separately formed movable receptacles, partitions separating the receptacles, the receptacles being adapted to be moved into and out of position between the partitions, a movable latch member extending past all of the receptacles, the partitions serving to

arrest the movement of said latch member in a position in the path of movement of the receptacles, and means for retaining the latch member in position engaging the partitions.

7. A record cabinet comprising a plurality of pivotally mounted receptacles, a stop member for limiting movement of the receptacles in one direction, a latch member for retaining the receptacles against movement in the other direction, a disk-shaped cover plate covering one of the receptacles, and said latch member comprising a section of wire extending past all of the receptacles having at least one of its ends bent to form a coil spring pivotally engaging about said stop member and being extended to detachably engage one edge portion of said cover plate, whereby the latch member may be resiliently maintained in latching position when desired.

8. A record cabinet comprising a base, an inverted U-shaped rod carried by said base having its ends attached to the base and having its opposite legs spaced apart and up-standing therefrom, and a plurality of receptacles pivotally mounted upon at least one of the legs of said U-shaped rod.

9. A record cabinet comprising a base, a U-shaped rod carried by said base having its ends attached to the base and having its opposite legs spaced apart and up-standing therefrom in substantially parallel relation, a plurality of disk-shaped partitions supported in superposed relation upon said spaced legs, and a plurality of receptacles pivotally mounted upon at least one of said legs between said partitions adapted to be swung into and out of position between the partitions for exposing the contents of the receptacles, the other of the legs being adapted to serve as a stop for limiting pivotal movement of the receptacles in one direction, and a latch member pivotally engaging about one of said legs adapted to be swung into a position in the path of movement of said receptacles for retaining the receptacles against movement in the other direction.

10. A record cabinet comprising a receptacle pivotally mounted to swing in a horizontal plane adapted to receive one or more disk record in a horizontal position, said receptacle having a bottom wall upon which the records rest, and having confining marginal walls for surrounding the records, and said bottom wall being cut away for a portion of its area so as to give access to the under surface of the records, whereby the records may be conveniently lifted from below to dispose their edges above the confining marginal walls of the receptacle.

11. A record cabinet comprising a plurality of separately movable receptacles, locking means for said receptacles, compris-

ing a pivotally mounted member extending past all of said receptacles adapted to swing into the path of movement of said receptacles, and said pivotally mounted member being resilient and having an integral extension therefrom, comprising spring means for yieldingly maintaining said locking means in locked position.

In testimony whereof we affix our signatures in the presence of two witnesses.
